UNITED STATES PATENT OFFICE

2,583,219

AIR-PRESSURE OPERATED DRAWER
CLAMPING MACHINE

Jeter M. Lancaster, High Point, N. C.

Application August 24, 1950, Serial No. 181,303

2 Claims. (Cl. 144—291)

1

This invention relates to apparatus used in the art of furniture construction for assembling drawers. More particularly, the invention has reference to an improved draw clamping machine of the type shown, for example, in my prior Patent No. 2,114,390, issued April 19, 1938.

It is an important object of the present invention to provide a generally improved construction for the drawer clamping machine.

Another important object is to provide an improved machine in which is embodied means for pressing on a drawer back, there being no such means illustrated in the previously patented apparatus, said back-pressing means being an air pressure operated overhead assembly and being particularly adapted for pressing on a drawer back when the drawer is made with female dovetails in the back edges of the drawer sides, or when the drawer is made in any other way that will require the back of the drawer to be pressed from another direction after the drawer front has already been pressed upwardly.

Another important object is to provide an improved construction wherein the clamping jaws are adjusted to operative position by an improved means comprising spaced screws linked for joint operation by means of a crank, chain, and spaced sprockets.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings:

Fig. 1 is a side elevation of the improved machine, portions being broken away.

Fig. 2 is a top plan view.

Fig. 3 is an enlarged vertical section through one of the jaws taken substantially on line 3—3 of Fig. 2.

Fig. 4 is a section substantially on line 4—4 of Fig. 3.

Fig. 5 is a perspective view of the back clamping bar of one of the jaws.

Fig. 6 is a fragmentary perspective view showing a portion of said back clamping bar and of a drawer engaged thereby showing how the drawer bottom is inserted.

Fig. 7 is a fragmentary rear elevation of the back clamping bar.

Fig. 8 is a top plan view showing the back clamping bar in position over a drawer.

Fig. 9 is a fragmentary section taken substantially on line 9—9 of Fig. 7.

Fig. 10 is a section substantially on line 10—10 of Fig. 3.

2

Fig. 11 is a somewhat diagrammatic side elevation of the clamping assembly as it appears when applied to a drawer with a half swelled front.

Referring to the drawings in detail, the machine constituting the present invention is mounted upon a supporting frame including the legs 1 suitably cross braced and braced longitudinally as at 2.

Side rails 3 are rigidly secured to the upper ends of the legs 1 and extend longitudinally of the frame in spaced parallel relation. On the respective side rails are rigidly mounted elongated flanges 4 each of which is formed with a longitudinal series of openings 5.

Flanges 4 constitute a slideway for the movable jaws, in a manner to be made presently apparent.

Mounted upon the outer surfaces of the side rails 3 and underlying the respective flanges 4 are the bearings 6 and 7 having smooth walled bores in which are supported for rotation elongated screws 8, said screws projecting beyond one end of the supporting frame and being there provided with sprockets around which passes a chain 9 linking the screws for simultaneous rotation. A crank 10 is mounted upon one of the sprockets. The screws are for the purpose of shifting one of the clamping jaws longitudinally of the frame in either direction, this being the jaw shown at the left in Fig. 1 and which for purposes of clarity in description will hereinafter be termed the left jaw.

Depending from opposite sides of the left jaw at the bottom end thereof are followers 10 in the form of internally threaded sleeves that are threadedly engaged with the respective advancing screws 8. Therefore, rotation of crank 10 in either direction will shift the sleeves 10 longitudinally of the supporting frame in either direction. The sleeves 10 are aligned transversely of the supporting frame.

The sleeves 10 are rigidly secured to the undersides of guide plates 11 that underlie the respective flanges 4 and are slideable therealong. The guide plates 11 are removably secured to opposite sides of a carriage 12 constituting the lower portion of the jaw and straddling the supporting frame. The carriage 12 overlies and is slideable upon the guide flanges 4, and thus the carriage 12 is mounted for sliding movement longitudinally of the supporting frame.

At this point, it should be noted that the left jaw is identical to the right hand jaw shown in Figs. 1 and 2, except for being oppositely disposed. Therefore, the description of the left jaw will suffice for and be understood as applicable to the right jaw. The main difference in the jaws resides in the fact that the guide plate 13 of the right jaw is not connected to the screw for thread-

ed advancement of the right jaw. Instead, the right jaw is freely slideable upon the slideway.

Referring once again to the left jaw, a primary adjustment of said jaw is made longitudinally of the supporting frame by operation of the crank 10. Thereafter, stop pins are dropped into the openings 5 immediately behind the jaw each stop pin including a knurled upstanding handle 14 connected to a bracket 15 rigid with the depending stud 16 extendable into a selected opening 5.

Threadable horizontally through the bracket 15 and against the carriage 12 is a fine adjustment screw 17. Thus, when the carriage 12 has received its primary adjustment, the stop pins are dropped into suitable openings immediately in back of the carriage, after which the screws 17 are threaded against the rear surface of the carriage. These thus serve as stop means whereby all pressure applied against the jaw in a horizontal path will not be shouldered by the threads of the advancing screws 8.

Integral or otherwise made rigid with the front surface of the carriage 12 are the transversely disposed horizontal draw front clamping bars 18, 19, and 20. As seen from Fig. 1, these are vertically spaced and each extends transversely across the supporting frame substantially from side to side of said frame.

Mounted upon the carriage 12 and upstanding therefrom a substantial distance is a cast standard 21 which, as readily seen from Figs. 4 and 10, is preferably of U-shaped cross section, this channeled construction being preferable for imparting strength to said standard.

An adjusting screw 22 is disposed vertically in the standard as best seen from Fig. 3, the adjusting screw projecting above the top end of the standard and being there provided with a hand wheel 23. The upper end of the screw is smooth-walled and bears in a smooth-walled opening 24 formed in the upper end of the standard.

Threaded upon the lower end of the screw 22 is an adjusting nut 25 underlying a slide 26 having the rearwardly extended projection formed with a smooth-walled opening 27 through which the screw 22 extends. Thus, the slide 26 can slide up and down upon the screw but is not threadedly engaged therewith.

The slide is mounted for vertical sliding movement in a vertical slot 28 extending substantially from top to bottom of the stand 21. Up and down movement of the slide is effected by threading of the nut 25 upwardly and downwardly on the screw 22, the underside of the rearward projection of the slide being formed with a recess receiving the upper end of said nut.

Rigidly secured to the slide 26 is a plate 29 straddling the slot 28, said plate 29 extending over a pair of guide flanges 29' formed upon the standard 21 and extending vertically to provide a slideway. Guide plates 30 are removably secured to the flanged side edges of the plate 29 to hold the plate 29 upon the standard during its up and down sliding movement on the standard.

Extended laterally from the opposite side edges of the plate 29, and formed integrally upon the plate, are ears 31 formed with threaded openings in which adjusting screws 32 are threaded, these being disposed horizontally and being each provided, as seen in Fig. 4, with a ball 34 universally movable in a ball socket formed in each end portion of a pressure plate 33.

In any position to which the respective screws 32 are adjustably threaded, they are capable of

being locked in position by means of a lock nut 35.

It will thus be seen that there is provided on each jaw a drawer side clamp, each clamp being vertically adjustable to a selected position and being provided with a pressure plate horizontally adjustable against a drawer side. A set screw 36 carried by the rear projection of the slide 26 engages the upper extension of the nut 25 to secure the slide 26 to said nut after the nut has been adjusted to a selected position.

In addition to each drawer side clamp, there is also mounted on each jaw a drawer back clamp. This includes a follower 37 having threaded engagement with the screw 22. The follower 37 slides in the slot 28 and is rigid with a slide member 38 straddling the front of the standard 21 and sliding on the flanges 29' of the standard, the slidable mounting of the member 38 being provided for by the guide plates 39 removably attached thereto and underlying the flanges 29' of the standard.

At this point, it will be apparent that by rotation of the hand wheel 23, both the drawer side clamp and the drawer back clamp will be adjusted vertically of the screw 22, that is, they will be simultaneously adjusted equal amounts up and down the jaw. However, apart from this simultaneous adjustment, the drawer side clamp is independently adjustable, since the nut 25 can be manually rotated to move it up and down the screw 22 while the screw is stationary. This is to permit adjustment of the side clamp and the back clamp relative to each other to accommodate different drawer formations.

Considering the construction of the drawer back clamp, there is rigidly secured to the slide member 38 an air cylinder 40 of conventional construction, this air cylinder being provided with the air pressure operated vertical plunger 41 extending downwardly and threadedly connected to a cross bar 42 the construction of which is particularly well illustrated in Fig. 5. A set screw 42' effectively locks the connection to prevent any rotatable movement of the cross bar relative to the plunger.

The cross bar 42 is provided with rearwardly extended flanges 43' to which are removably connected the guide plates 43, for slidable mounting of the cross bar 42 upon the lower extension 44 of the slide member 38. Thus, the slide member 38 is mounted for up and down slidable adjustment upon the stand 21, while the cross bar 42 is in turn slidable up and down upon the slide member after the slide member has been adjustably positioned at the desired height.

Pivoted connected at its center to the center portion of the slide 42 is a clamping bar 45 of right angled cross section, having the depending longitudinal flange 46. This pivots in a horizontal plane and regardless of the direction in which it is pivoted, is returned to a normal position as seen in Fig. 5, wherein its front surface is flush with the front surface of the member 42. For accomplishing this I provide, as seen in Figs. 7 through 9, a pair of rearwardly extending pins 47 threadedly connected to the clamping bar 45, these pins extending rearwardly from the clamping bar at opposite ends thereof. Surrounding these pins are springs 48 abutting at one end against the clamping bar and at the other end against depending extensions of the member 43, that is the guide plates whereby the slide member 42 is mounted for up and down sliding movement upon the air cylinder slide 38. Said depending extensions of the guide plates 43 are

formed with slots 49 through which the pins 47 extend, slots being utilized at this location instead of smaller openings, in order to permit lateral movement of the pins relative to the guide plates whenever the clamping bar 45 is pivoted upon the slide 42.

At opposite sides of the pivotal mounting thereof, the clamping bar 45 is chamfered as at 50, for a purpose to be presently made apparent.

On each of the jaws, I provide the L-shaped supporting rods 52, mounted for vertical swinging movement in brackets 51, and adapted to be held in any position to which adjusted by thumb screws 52'. These serve as drawer stops, to hold the sides of the drawer at any desired position while the drawer is being clamped. As will be appreciated, the rods can be adjusted by loosening the thumb screws 52', whereupon the rods are swung to the desired new position of adjustment and again locked in position.

On each of the right and left jaws, I provide bottom supports for the drawer fronts, the construction thereof being particularly well shown in Fig. 1. Each of these includes adjusting screws mounted in horizontally spaced vertically disposed threaded sleeve 53, said adjusting screws being designated 54 and being threadable upwardly and downwardly in said sleeve. The sleeves 53 of each carriage are rigid with their respective carriages 12 and depend from adjacent sides thereof so as to be positioned in the space between the respective side rails of the supporting frame.

Each screw 54 is threadable upwardly against, and supports, a vertically swingable arm 55 swingably mounted upon a bracket 56 also rigid with the carriage 12 of the jaw.

When the screws 54 have been threaded to a selected position, they are locked in said position by means of lock nuts 57.

By reference to Fig. 2, it is seen that an arrangement including the thumb screw 54 and arm 55 is provided at each side of the jaw, adjacent the guide flanges 4. Thus, the arms 55 provide bearings that are spaced transversely of the supporting frame and that are swingably adjusted upwardly and downwardly, these bearings supporting opposite ends of a rock shaft 58 rigid with the transversely extending rest 59 in the form of a flat bar adapted to underlie a drawer front. The rockable mounting of said rest 59 adapts it to drawer fronts of any configuration, whether they be curved or straight.

When the rest 59 has been rockably adjusted into engagement with the particular drawer front, it is held in said position by means of set screws 60 threadable through the arms 55 against the rock shaft 58.

I also provide a middle rest for the drawer front, which in some instances will not be necessary if the drawer is rather short. However, if the drawer is long, it is desirable to provide a suitable support for the medial portion thereof, to prevent buckling or sagging thereof, when pressure is applied to opposite ends of the drawer front by the clamping surfaces 18 of the respective drawers.

With respect to this medial support, centrally disposed between opposite ends of the supporting frame is a vertically threadable screw 62, threadable through a cross bar 61 rigid with the opposite side rails 3. A lock nut 63 locks the screw 62 in selected positions of threadable adjustment.

Supported upon the upper end of the screw 62,

is a middle rest 64 in the form of a flat bar having raised ends 65 overlying the guide flanges 4.

A fragment of a drawer is illustrated in Figs. 6 and 8 respectively and includes drawer sides 66, a drawer bottom 67 receivable in the groove 68 of the drawer sides, and a drawer front 69. In this connection, a drawer such as is to be completely assembled in the present apparatus is generally made up of five parts. The drawer front 69 is formed with female dovetails along the inside edges of each end of the drawer front. The drawer sides 66 are formed with male dovetails on their front edges and with female dovetails at their back ends. The drawer back, not illustrated in Figs. 6 and 8, is formed with male dovetails at both ends. The drawer bottom 67 is usually a piece of plywood or similar material, fitting into a groove which is cut at the bottom of the drawer front, drawer back, and the drawer sides.

Another type of drawer adapted to be assembled by the machine is illustrated in Fig. 11. In this drawer there is a drawer back 70, and drawer sides 71, the drawer sides 71 being of unequal lengths, in view of the fact that the drawer is of the half swelled front type. The half swelled front is designated 72, and as will be seen, it is longitudinally curved toward one end of the drawer.

The manner in which the drawers are assembled will be described in detail hereinafter.

Completing the formation of the apparatus is the control and power means thereof. An air line 73 is connectable to any source of air to be supplied under pressure. This air is directed through an air regulating valve 74 of conventional construction after which the air passes through a foot controlled valve 75 of a type including a rockable foot pedal which, when rocked in one direction, will remain in the position to which rocked until released by foot pressure, rocking it back in its previous position.

The air supplied under pressure in this manner is directed through hoses 76, to an air pressure cylinder 77 mounted upon a suitable bracket beyond one end of the supporting frame. The air cylinder 77 actuates a plunger 78 engaging the rear surface of the right jaw, so as to force said jaw to the left in Fig. 1. Stop pins 79 limit movement of the jaw under pressure. These stop pins have two purposes. One is to enable the operator to adjust the length of the stroke of the plunger 78 and right hand jaw, and it will be apparent that on removal of the stop pins 79, a longer stroke can be given the jaw. The other purpose is to hold the right jaw perfectly square so as to give uniform pressure against the drawer fully transversely of the drawer. As will be seen, not only do the stop pins hold the drawer perfectly square in this manner, but also, they constitute a restraint that holds the pressure against the drawer at the desired point without damaging the drawer through application thereto of excess pressure which otherwise might result if the restraint did not exist, and the drawer was pressed against by the right jaw under the full pressure of the ram or plunger 78.

Another air regulating valve 80 is mounted upon a line 80' that also extends from the air inlet 73. This valve regulates air to be fed through lines 81 to the cylinder 40 of the left jaw. The feeding of air to the cylinder 40 is controlled by a foot pedal 82.

As will be noted, there are supply lines 81 to both of the cylinders 40, so that air is fed in

equalized amounts to both of these cylinders simultaneously, by depression of the pedal 82.

Considering now the use of the machine, as previously noted the machine should first be connected to a source of air to be fed under suitable pressure, as a first step, the foot pedal 75 is shifted to one position, applying pressure to the right jaw to cause said jaw to move toward the left in Fig. 1 against the stop pins 79.

Then, by operation of the crank 10, the left jaw is shifted toward the right in Fig. 1, that is, toward the right jaw, the jointly rotated screws 8 holding the left jaw perfectly square during said movement.

Assuming that the drawer to be assembled has a flat front 69 as distinguished from a curved front such as that seen in 72, it will be understood that the left jaw will be adjusted until the drawer front can be supported at opposite ends upon the rests 59.

The rests 59 will now be adjusted upwardly or downwardly as necessary until the clamping surfaces 18 of the right and left jaws are in line with the female dovetails of the drawer front and are just above the lips formed at opposite ends of said drawer front. These lips will engage under the clamping surfaces 18.

When this adjustment has been made, the rests 59 are locked in their positions of adjustment by means of the lock nuts 57 and set screws 60.

At this stage, the clamping surfaces 18 of both jaws should be tight against the dovetails of the drawer front.

The next operation is to square the drawer side clamping bars 33 with the clamping surfaces 18 by loosening the lock nuts 35 and adjusting screws 32 to the desired position, after which the lock nuts are again tightened to hold the screws in their selected positions of adjustment.

Air pressure against the right jaw is now released by return of the foot pedal operated valve 75 to its first position. The drawer sides 66 are now placed in position at each end of the drawer front, with the male dovetailed ends of the drawer sides in line with the female dovetailed ends of the drawer front. Air is applied once again to clamp the interengaging dovetails. The apparatus is now properly set up for clamping the drawer back. As a first step, the slide member 29 of each of the drawer side clamps is independently adjusted relative to the clamp bars 45 so that the clamping flange 46 of said bar 45 will not contact the side clamping bar 33 when pressure is applied to the overhead air cylinders 40. This adjustment is effected by loosening of the set screw 36, after which the nut 25 is manually threaded upwardly or downwardly as necessary, until it is in the proper position.

The set screw 36 is now tightened once again.

The hand wheel 23 is now operated to lower the top and side clamping units, until the clamping bars 33 are approximately one inch below the back end of the drawer sides 66, which drawer sides will be vertically positioned during the assembly of the drawer so that the back ends thereof will be at the top.

When the hand wheel 23 is operated, it will simultaneously adjust the top clamping bar 45 and the side clamping bar 33 equal distances.

At this stage, the drawer bottom 67 is slid downwardly past the clamping bars 45, which as previously noted are chamfered and centrally pivoted, to allow passage of the drawer bottom as it moves into the grooves 68.

When the drawer bottom is fully inserted in

the grooves, the clamping bars 45 will spring back to square position by action of the springs 48. When the clamping bar 33 is sprung backwardly to its previous position in this manner, it serves as an overhead clamping bar.

The operator now places the male dovetails of the drawer back in line with the respective female dovetails in the back end of the drawer sides. Air is now applied to the overhead cylinders 40 and this results in clamping of the dovetails at both ends of the drawer back squarely into position, the ram or plunger 41 forcing the member 42 downwardly which of course carries downwardly the overhead clamping flange 46.

Should the drawer be unusually long, the center rest 64 is employed, this being manually slid to a location wherein it is approximately centrally positioned between the jaws. The screw 62 is then utilized to force the center rest upwardly until it will support the center part of the drawer front to be clamped, after which the lock nut 63 holds the rest in its adjusted position.

As previously noted, there are spaced vertically aligned clamping surfaces 18, 19, and 20 on each jaw. In clamping of a flat front drawer, the surface 18 would be used in the manner previously noted. However, the additional clamping surfaces 19, and 20 make it possible to clamp a drawer with a half swelled front such as illustrated in Fig. 11, or with a flat or straight front but with drawer sides of different lengths. Such a drawer is readily assembled, and in the illustrated example, one end of the drawer front is engaged by the clamping surface 18 of the right jaw, while the other end of the drawer front is located to receive its pressure from the clamping surface 20 of the left jaw. The rest 59 of the left jaw is adjusted upwardly a greater extent than the rest 59 of the right jaw. Despite this irregular jaw formation, the drawer back, which is located to receive pressure from the overhead cylinder 40, remains perfectly square with said overhead cylinders.

What is claimed is:

- 45 1. In a drawer assembly machine a supporting frame; a pair of jaws mounted upon said frame for sliding movement toward and away from each other; standards upstanding from the respective jaws; feed screws rotatably and vertically mounted in the respective standards; a drawer back clamp slidably mounted upon the standard and having threaded engagement with said feed screw, for up and down adjustment of the drawer back clamp responsive to rotation of the feed screw; and a drawer side clamp slidably mounted upon the standard and having threaded engagement with said feed screw, for adjustment simultaneously with the drawer back clamp, said threaded engagement of the drawer side clamp being adapted for threaded adjustment of the drawer side clamp upon the feed screw independently of adjustment of the drawer back clamp, for spacing the drawer side and drawer back clamps selected distances apart prior to simultaneous adjustment vertically of the standards.
- 60 2. In a drawer assembly machine a supporting frame; a pair of jaws mounted upon said frame for sliding movement toward and away from each other; standards upstanding from the respective jaws; feed screws rotatably and vertically mounted in the respective standards; a drawer back clamp including a slide member slidably mounted upon the standard and having threaded engagement with said feed screw, for up and down

adjustment of the drawer back clamp responsive to rotation of the feed screw; and a drawer side clamp slidably mounted upon the standard and having threaded engagement with said feed screw, for adjustment simultaneously with the drawer back clamp, said threaded engagement of the drawer side clamp being adapted for threaded adjustment of the drawer side clamp upon the feed screw independently of adjustment of the drawer back clamp, for spacing the drawer side and drawer back clamps selected distances apart prior to simultaneous adjustment vertically of the standards, an air cylinder rigidly connected to the slide member; an air plunger extending from said air cylinder and having up and down movement independent of the vertical slidability of the slide member; a second slide member slidably mounted upon the first slide member and engaged by said plunger; and a clamping bar pivotally connected to the second slide member for 20

swinging movement in a vertical plane, said clamping bar including means yieldably retaining the clamping bar in a position in which it is square with the second slide member.

JETER M. LANCASTER.
